CLAIM

I claim the ornamental design for a bowl for soup or sugar,
as shown and described.

DESCRIPTION

FIG. 1 is a front elevational view of a bowl for soup or sugar
showing my new design, the rear elevational view being a
mirror image thereof;FIG. 2 is a left side elevational view, the right side elevational
view being a mirror image thereof;

FIG. 3 is a top plan view; and,

FIG. 4 is a bottom plan view thereof.

The pattern visible in FIG. 3 is continuous, and does not
contain a break. The visible break in FIG. 3 is caused by a
reflection.
